Specification for Design.

Patented Nov. 16, 1909.

Application filed July 17, 1909. Serial No. 508,251. Term of patent 14 years.

To all whom it may concern:

Be it known that I, BERNARD A. STOWE, a citizen of the United States, and a resident of Cleveland, county of Cuyahoga, and State of Ohio, have invented a new, original, and ornamental Design for Brackets for Supporting Fans and the Like, of which the following is a specification, reference being had to the accompanying drawing, forming part thereof.

In said annexed drawing:—Figure 1 is a

side elevation of a bracket for supporting fans and the like showing my new design; and Fig. 2 is an end elevation of the same.

I claim:—

The ornamental design for a bracket for supporting fans and the like, as shown.

BERNARD A. STOWE.
